UNITED STATES PATENT OFFICE.

LOUIS VICTOR WILLIAM FROGER, OF LORIENT, FRANCE.

TOWING APPARATUS.

1,016,619.

Specification of Letters Patent.

Patented Feb. 6, 1912.

Application filed March 29, 1909. Serial No. 486,298.

To all whom it may concern:

Be it known that I, LOUIS VICTOR WILLIAM FROGER, a citizen of the Republic of France, residing at Lorient, Morbihan, France, have 5 invented certain new and useful Improvements in Towing Apparatus, of which the following is a specification.

Whatever their nationality all ships or boats are towed by means of two cables or 10 tow ropes connecting the towing boat with that which is towed. For this purpose there are used the four projections called bitts with which each boat is customarily provided and which are arranged laterally two 15 on each side at a suitable distance forward and aft. This use of two completely independent ropes makes it very difficult to adjust their length so that they are subjected to an equal degree of tension; moreover 20 when the adjustment has been made each variation in direction necessitates re-adjustment, which is a very difficult and dangerous operation while the vessel is moving; indeed it is practically impossible. Approximate- 25 ly speaking, the two ropes support alternately the tractive force every time the directions followed by the towing and towed boats differ. The ropes thus become fatigued and the constantly varying tension 30 affects their strength as well as that of the parts to which they are attached, making them very dangerous to the seamen. Moreover these lateral bitts are frequently of no 35 use because of their lack of security when the sea is at all high. For this reason on many sailing boats or steam boats it is preferred to use the main mast, and on certain vessels of war, the turrets, because of the absolute security which these fixed points afford. On the bitts the tow ropes are rolled 40 into coils and around the main mast or the turret in rings, this operation being extremely long and difficult and often dangerous to the seamen who have to perform it, especially when the boat is of considerable 45 tonnage and the ropes are of a large diameter, lacking suppleness; moreover the coiling of each rope on the fixed points of the towing boat and of the towed boat diminishes the length of the rope to the great 50 detriment of its elasticity. Of course when it is necessary to cast off the ropes the work is not less long, delicate, difficult or dangerous.

55 The object of this invention is an endless

tow rope designed for the purpose of remedying the aforesaid inconveniences and many others which follow the use of the customary independent ropes and their mode of connection with the boats.

According to the invention the lateral or axial points of attachment of the ropes both on the towing vessel and the towed vessel are no longer fixed; the principle of two independent ropes is also abandoned and for the fixed points of attachment of the ropes there are substituted both on the towing boat and on the towed boat two axial bitts, one forward and the other aft, at an appropriate distance from the ends of the vessel, 60 fixed directly on the deck or the lower part of the main mast, each of these bitts carrying a pulley adapted to revolve on its axis; or there may be four bitt-pulleys fixed at 65 the sides of the vessel to the deck, two at 70 the prow and two at the stern at a suitable distance from the ends of the vessel. Around these pulleys the endless tow rope passes.

75 Two modes of towing are contemplated by 80 the present invention, one in which there are two axially placed bitt-pulleys, the other in which there are four lateral bitt-pulleys.

The first, which is the more economical and the more practical, should be used in 85 preference to any other on all steam vessels which have no bowsprits or other projections like guns, as on these vessels there is a free space about the axis of the vessel at each 90 end, such a space being essential to this mode of towing. For ships of war and merchant vessels having a bowsprit in which the presence of poop and forecastle allows the use of axial bitt-pulleys for towing, the said 95 pulleys must be made as little cumbrous as possible, and they should be simple and economical on any kind of vessel; two sorts of bitt-pulleys for the purpose may be distinguished, corresponding with the three 100 following cases:—(1) An axial bitt-pulley fixed to the deck when the main masts fore and aft cannot be used as axles for the pulleys; (2) an axial pulley through which the main mast is passed before it is stepped so 105 that it may serve as the axle of the pulley; (3) an axial pulley adapted to be fitted to the main mast, which is to serve as its axle, after the mast has been stepped, thus avoiding the onerous operations of un-stepping 110 and re-stepping the mast.

The second mode of towing, namely with four bitt-pulleys, is of more general application; it is applicable to all war ships and merchant vessels whether steam boats or sailing boats.

In order that the invention may be well understood reference will be made to the accompanying drawings, which however, merely illustrate types of the invention.

- 10 Figure 1 shows in part plan a towing boat and a towed boat connected by an endless tow rope according to this invention. Fig. 2 shows, drawn to an enlarged scale, a side view of a part of the endless tow rope which 15 is used for connecting together the elements of the rope which pass around the pulleys on the respective vessels. Fig. 3 is a plan drawn to an enlarged scale of the shackle that connects the elements of the towing 20 rope. Fig. 4 is a vertical section on the axial line of Fig. 3. Figs. 3^a and 3^b show respectively a variation of the shackle and a detail thereof. Fig. 4^a is a plan of the end of a vessel from which the shackle shown in 25 Fig. 3^b is operated. Figs. 5 and 6 are respectively longitudinal sections and plans of one kind of pulleys for the endless rope provided with devices for limiting the travel of this rope in the two directions; Figs. 7 30 and 8 are like views respectively of a modification. In Figs. 5 and 6 the pulley is adapted to be used on vessels in which the masts cannot be employed for towing. Figs. 7 and 8 show an axial pulley having a main 35 mast as its axle, the mast being introduced into the pulley at the time it is stepped or the pulley being applied to the mast after it has been stepped. Fig. 9 is a part elevation of a towing boat and a towed boat connected 40 with each other by a variation of the endless tow rope. Figs. 10 and 11 are respectively an elevation and a plan of a towing boat and a towed boat connected with each other by an endless rope passing around four pul- 45 leys. Fig. 12 is a side elevation of the key for operating the shackle release. Fig. 13 is a partial elevation of a gaff provided with a. steel cable and designed for opening the shackle release. Fig. 14 is a cross section of 50 Fig. 11. Figs. 15 and 16 are respectively an elevation and a plan of two harbor towing boats both constructed on the same model, one of them, the auxiliary towing boat, being coupled to an intermediate boat which may 55 itself be supposed to be coupled at its stern with a stranded vessel. Figs. 17 and 18 are a side elevation and a plan of a device for connecting a main mast to a pulley for the endless rope. Figs. 19 and 20 are respec- 60 tively an elevation and a plan of another device for connecting the hull of the towing boat at each side, fore and aft, with a pulley for the endless rope which passes trans- versely above the deck. Fig. 21 is a plan of 65 a single pulley of double action. Fig. 22 is

a plan of a bitt-pulley situated in the trans- 70 verse plane of the vessel. Fig. 23 is a plan of a vessel, of which the bitts have been transformed. Figs. 24 and 25 are respec- 75 tively a side elevation and a plan drawn to an enlarged scale of bitts provided with a sleeve device.

Reference will first be made to the mode of towing by an endless tow rope passing over two axially placed pulleys (Fig. 1). 75 It may, however, first be remarked that the two kinds of pulleys represented in Figs. 5, 6, 7 and 8 comply satisfactorily with the three cases cited above. The bitt-pulley shown in Figs. 5 and 6 is suitable for vessels 80 the main masts of which cannot be used for towing. The other type of pulley (Figs. 7 and 8) may be applied to any main mast that can be used as the axle of the pulley, either at the time of stepping the mast or 85 afterward.

Before introducing the foot of the mast into its step the mast should be put through each organ of the pulley in the following order:—upper cheek, sheave, lower cheek, 90 and its base plate, the deck and its reinforce- 95 ment, (Figs. 7 and 8). When the mast has been stepped each part of the pulley of suitable dimensions is cast in two sections along the vertical transverse plane, so that 95 each section of the upper cheek, the sheave, the lower cheek and the reinforcement plate can be assembled with the corresponding section and bolted to the mast or to the deck. As to the sheave, the two sections are pro- 100 vided with dovetails of steel either cast on the section or fitted thereto.

In Fig. 1, 1 and 2 are bitt-pulleys which are fixed at the prow and the stern of each vessel and constructed in either of the forms 105 shown in Figs. 5 to 8, the former having its own axle while the latter has the mast for an axle.

Apart from certain details the two kinds of pulleys are sufficiently alike to render 110 the description of Figs. 5 and 6 applicable to Figs. 7 and 8.

A steel plate 1^a strengthens the deck 1^b beneath the base plate 1^c of the bitt (Figs. 5 and 7). The base plate 1^c is cast in one 115 with the cheek 2^a, and between this cheek and the sheave a ball bearing 3 is inter- posed. A square opening 4 (Figs. 5 and 6) or cylindrical opening 8 (Figs. 7 and 8) is provided in the lower cheek 2^a, the base 120 plate 1^c, the deck 1^b, and the strengthening plate 1^a, to receive the squared part of the axle 4^a (Figs. 5 and 6) or the cylindrical mast 4^b (Figs. 7 and 8).

The plate 1^c, the deck 1^b, and the plate 1^a 125 are connected together by bolts or rivets, and the axle 4^a extending through the deck and the plate 1^a is held in place by a nut duly locked. The sheave 5 turns on the cylindrical part of its cast steel axle 6 (Fig. 130

5), or, as shown in Fig. 7, on a sleeve 6^a cast in one with the lower cheek 2^a and riveted to the mast so as to constitute with this the axle. The cylindrical portion of the axle 6 (Fig. 5) has a shoulder which rests upon the cheek 2^a, thus fixing the distance between the upper cheek 7 and this lower cheek 2^a. In Fig. 7 the upper cheek 8 has a part 9 which rests upon the upper edge 10 of the sleeve on which the sheave turns. The sheave 5 turns on a ball bearing 3^a and is grooved on its periphery to receive one of the elements of the tow rope, which element may be called the pendant.

15 Each pendant 10 is connected at its ends with the corresponding ends of the other pendant by the connecting ropes 11, the connection being made by special shackles as will now be described. Each end of the connecting rope 11 has a metallic eye 12, through which is passed a plain link 13, itself attached to a bent link 14, Figs. 2 and 3. Each end of the pendant 10 is attached by means of an eye 12 to the middle 25 part of a shackle 15, the bolt 16 of which has screw threaded ends to receive nuts 17 locked by pins 18. A suitable washer is interposed between each nut and the shackle. The middle part of the bolt 16 has an arm 30 19 which, when it is in the position shown in Fig. 3, prevents the bent link 14 of the connecting rope 11 from becoming detached, while when the bolt 16 is turned through a quarter of a revolution on its axis in the direction of the arrow in Fig. 4 there is nothing to prevent detachment of the link 14 from the bolt 16; in order thus to turn the bolt 16 there is provided a handle 20 fixed on one of the nuts 17.

40 To keep the arm 19 in its locking position there is fixed to the limbs of the shackle a cross bar 22 of cast steel carrying at each end a collar embracing the corresponding limb. At the middle of this cross bar there 45 is a cylindrical bore adapted to receive a short axle 24 which turns in the bore on a ball bearing 23 and is held in place by a nut 26 locked by a pin 27 on the end of the axle, the washer 25 being interposed between the nut and the cross bar. The other end of the axle carries a socket 28 of cast steel and suitable dimensions, in one side of which is an opening 29 to permit passage of the end of the arm 19. When the end 55 of the arm 19 has been introduced into the socket 28 through the opening 29 and the latter has been turned through a quarter of a revolution, unintended detachment of the parts of the tow rope is impossible. When 60 it is desired to disconnect the pendant 10 from the connecting ropes 11 on one of the vessels it is only necessary to turn in the opposite direction, by a key 30 applied to the nut 26, which may be operated through 65 a distance by a cord, the socket 28 through

a quarter of a revolution in the reverse direction to that in which it was turned to lock the bent link 14 in order to liberate the arm 19 and to permit the desired disconnection.

70

Instead of controlling the socket 28 by a key 30, which presents a certain degree of risk in that it may catch upon the deck or on the hull, the socket may be turned by means of a chain wheel 30^a (Fig. 3^b) or an eccentric wheel 30^b (Fig. 3^a) having two flanges 25^a and mounted on the squared portion 30^c of the axle 24. Over this wheel, which is protected by the two limbs of the shackle, passes a chain 29^a adapted to be 80 operated in any suitable manner from the vessel.

75

On the front end of the towed boat and on the rear end of the towing boat there are fixed, between the sides of the parallelogram 85 formed by the endless tow rope and in a plane higher than that which contains this rope, two eye bolts 36 at a distance from each other slightly greater than that through which the shackles 15 have play. 90 In these eye bolts, two of which are fixed on each side of the deck, is fixed a steel cord 37 on which is threaded an eye 38, a groove in the periphery of which serves as a pulley groove for the chain 39 which controls the wheel 30^a. The cord thus constitutes a guide for the eye 38. 95

When the chain 39 has been operated so as to turn the socket 28 through an angle of, say, 180°, the two sides of the chain can be 100 equalized by allowing the chain to slide in a groove of the eye 38 to compensate for pitching and rolling movements of the vessel, and then the two sides of the chain are 105 brought together below the eye 38 and are tied by a cord or otherwise, in such a manner that the connection can be readily severed. Owing to this arrangement, as the shackle moves to and fro, the eye which constitutes a carriage for the chain will 110 slide with it, the movement of the eye being in opposite directions on the two sides of the deck. In order to cast off the tow rope the connection between the two sides of the chain 39 on each side of the vessel is severed and one of the sides of each chain is pulled either by hand or by a rope attached to each chain so as to turn the wheel 30^a through the required angle and thus to liberate the tow ropes from the shackles simultaneously. 120

It will be seen that when the two elements of the endless tow ropes have been connected with each other the two parts of the tow rope which pass around the bitt-pulleys can 125 always equalize themselves in length by causing the sheaves 5 to turn on their ball bearings. It will be seen from Figs. 1 and 11 that there are four combinations possible under this system of towing. The first 130

(Fig. 1) is towing by means of axial bitt-pulleys. The second (Fig. 2) is towing by means of four lateral bitt-pulleys. The third is a combination of the first and the second, a vessel provided with axial bitt-pulleys towing another vessel provided with lateral bitt-pulleys. The fourth is a combination of the second and the first a vessel provided with lateral bitt-pulleys towing another provided with an axial bitt-pulley. Now, in the first two combinations the endless rope is in the form of a parallelogram, while in the other two it is in the form of an isosceles triangle. In the four combinations the figure formed by the ropes is perfectly symmetrical with reference to its longitudinal axis and consequently the strains are always perfectly symmetrical and consequently balanced. Therefore the cables are always equally under tension and the breaking of them is avoided.

In order that in case of unforeseen rupture of one of the connecting ropes 11 of the towing boat, the pendants 10 may remain around the respective sheave, it is necessary to limit their travel on these sheaves. For this purpose there is threaded on each pendant two blocks 31 acting as stops. These are of cast steel of suitable dimensions and strength. They are of the form of a truncated cone and have a conical bore with rounded angles to accommodate the splicing of the rope around the eye 12 and such that not even the most violent strain could bring the block over the eye. Since the pendants 10 have to withstand the whole strain of the towing their tensile strength should be double that of each connecting rope 11. Both the pendants and the connecting ropes may be hemp cables, metallic cables or chains. It follows that a vessel may use its ordinary tow ropes by coupling them with links as indicated in Fig. 2, and may even make up its own pendants if it is supplied with the necessary shackles 15, the connections being made as indicated in Fig. 3.

Although the arrangement hereinbefore described suffices to make the endless tow rope quite secure, the safety of the system may be increased by the following additional precautions. In order to avoid permanent friction, which might diminish the strength of the connecting rope 11, there may be inserted between each pair of links 13, 14, a length of chain 32 as in Fig. 9. Moreover, in towing by means of axial bitt-pulleys, it may be useful, while allowing the endless rope as much play as possible on the poop or forecastle, to limit this play on each side of the longitudinal axis of the vessel by two posts 33 carrying wheels as indicated in Fig. 9, where, however, the posts are shown in the axial line of the vessel instead of to the left and right thereof. In order to obtain a sufficient elasticity in the

two connecting ropes in spite of the considerable tractive force, it is advantageous to cut the ropes at their middle part and to re-unite them by a chain 34 of suitable length and diameter, so as to have a deep catenary curve in the middle of each rope. 70

The mode of towing shown in Figs. 10 and 11 only differs from that which has been described in that there are four lateral bitt-pulleys instead of two axial pulleys. 75 The endless rope passes around each of these pulleys. It may be pointed out what, in this mode of towing is borrowed from that first described:—1. The endless rope is composed of the same elements as those shown in Figs. 1 and 2 and a length of chain is introduced into the middle of each connecting rope 11 as in Fig. 9 to insure as much security as possible for the rope. 2. Each fore and aft pendant on each vessel is of a suitable length so selected that neither of the shackles 15 ever passes the end of poop or forecastle in order that it may be easy to connect and disconnect the connecting ropes 11. 3. On each steam or sailing vessel which does not use the first mode of towing are mounted two lateral bitt-pulleys, fore and aft, at a suitable distance from the ends of the vessel. These bitt-pulleys are of the type represented in Figs. 5 and 6, but each only possesses one of the eyes 7 for engagement with the stop 31; they are fixed at the sides of the vessel in a manner similar to that described with reference to Figs. 5 and 6 and project slightly over the sides so as to avoid friction of the shackles 15 against the sides. 90

The key 30^a which serves to turn the socket 28 may be operated from the poop or forecastle by means of a gaff (Fig. 13) which can be hooked over a projection 35 on the key (Fig. 12) so as to turn the latter through an angle of 45° so as to liberate the arm 19 from the socket 28. The key 30^a may also be operated in the following manner (see Fig. 4^a):—To the side of the ship and to the deck are fixed two eye bolts 36 through which slides freely a rope 37 whereon is threaded a metal eye 38 free to move between the two eye bolts 36; to this eye is spliced a metal gasket 39 attached at its other end to the key 30^a. The two ends of the rope 37 engage a tackle 40 (Figs. 10 and 11) which can be quickly shortened. If now the length of the gasket 39 is less than the distance which separates the key 30 from rope 37 it is only necessary to haul on the tackle in order to turn the key or both the keys. If a third eye bolt 36^a be provided, the rope 37 may be slackened. 110

It may be noted that these two modes of towing, such as have been described with reference to Figs. 1, 9, 10 and 11 permit a working almost as regular as that of the towing machine and a freedom of evolution greater than that of vessels having inde- 125

pendent tow ropes, on account of the elimination of hitching and belaying. The length of the connecting ropes 11 is moreover increased to the great advantage of its 5 elasticity, and the compressions, frictions, deformations and fatigue of the strands of the rope are supported completely by each pendant 10. The attachment and detachment of the towing boat 10 is performed in a manner resembling the harnessing of a horse to a carriage, each of these operations requiring a very short time; it is never necessary to equalize the connecting ropes either by taking them 15 on board or while towing, and in both modes of towing manipulation of the ropes is not accompanied by danger to the operator owing to the fact that the ropes do not require to be hitched. When towing for floating 20 stranded vessels other connections should be provided in addition to the bitt-pulleys already described either on the deck, such as on the mast, or on the external surface of the hull (Figs. 15, 16). On each main 25 mast may be fixed a steel sleeve 41 having a flange 42 and above this a steel collar 43; a bolt 45 (Figs. 17 and 18) extending through lugs 44 of this collar holds a link 46 connected with a shackle 47 holding a 30 steel pulley 48. On each side of the vessel fore and aft at the junction of the deck, the beams and the wall, and outside the latter, is fixed a strong longitudinal tire-iron 49, the eye 50 of which (Figs. 19 and 20) receives 35 the link 46 connected with the shackle 47 carrying the pulley 48 (Figs. 19 and 20). The pendants 10 are passed around the pulleys 48, the sides of the vessel having ports to render this possible for the external 40 pulleys (Figs. 15 and 16). In this manner there may be used for floating the stranded vessel eight endless tow ropes. To avoid strain which these tow ropes would produce 45 on the intermediate towing vessel yoked in tandem to the vessel to be floated and the towing vessel, tending to rupture it, the tow ropes should be crossed by connecting the ropes of the front towing vessel on the stern of the intermediate vessel and those of the 50 grounded vessel on the prow of the intermediate vessel. A pair of lateral bitt-pulleys of the type indicated in Fig. 22, fixed firmly to the end of the transverse plane 55 passing through the center of gravity of the towing boat, permit of towing and of being towed by interposing the pendants 10 according to the case. Finally a single bitt-pulley of the model shown in Fig. 21 fixed 60 on the spar-deck of a towing boat driven by internal combustion engines without a chimney having one mast near the said bitt-pulley bolted to the intersection of the longitudinal and transverse planes passing through the center of gravity of the boat, 65 also allows of economical towing.

It must be remarked that the bitt-pulleys shown in Figs. 21, 22, are similar to those shown in Figs. 5 and 6 and only differ from the latter in the number of eyes 7. On sailing vessels or steam vessels which are being 70 designed or in course of construction, when in face of the total cost of construction the expense will be insignificant, it is preferable to fit four bitt-pulleys, one pair forward and the other pair aft for receiving the towing 75 pendants. Owing to these bitt-pulleys, the endless towing rope applied to the two vessels similarly arranged, presents a parallelogram of which the four sides operate 80 equally, the pendants slipping or rolling on the sheaves of the pulleys. On vessels which are already afloat the endless tow rope can be used even more economically. On all these vessels, if they are armored, it is essential to have two sets of simple bitts or 85 posts, one fore and the other aft. The arrangement of sleeve described below and shown in Figs. 23, 24, 25, allows these sets of bitts to be adapted in a simple, rapid and economical manner for the purpose of 90 using them with the endless tow rope.

On each simple bitt, or on each bitt post L, fore and aft of the vessel, it suffices to fit a steel sleeve M of suitable height and thickness, which sleeve has for its object not only 95 to protect each simple bitt or post from friction but to connect firmly together the two posts of each bitt, so as to allow the towing pendant 10 to slide. It will be obvious that every vessel afloat having these 100 sets of bitts may be provided with a single pendant chain 10 of suitable resistance and having two disconnecting shackles to enable the vessel to tow or to be towed by rigging up this chain on the fore and aft bitts as 105 the case may be. It will be evident that on each of these pendant chains 10 may be hooked each towing rope carried by the respective vessels, the chains sliding around the bitts. 110

Having thus described the nature of my invention and the best means I know of carrying the same into practical effect, I claim:—

1. A towing apparatus for marine vessels 115 comprising a cable in four parts, readily attachable and detachable connectors connecting said four parts into an endless cable, the cable being arranged with two of its parts extending between the towing boat and the towed boat symmetrically, and each of the other two parts of the cable being looped around fastening means on one of the boats and movable freely about said fastening means, thus tending to equilibrate the strains. 120

2. Towing apparatus for marine vessels 125 comprising four ropes, a shackle attached to each end of each of two of these ropes, a bent link attached to each end of each of the other two of these ropes, an arm carried 130

- by each shackle bolt and adapted to engage a bent link, a socket mounted on an axle adapted to rotate and carried by the shackle, the said socket being adapted to receive the 5 said arm and to liberate it when the said axle is turned through an angle.
3. Towing apparatus for marine vessels comprising four ropes, a shackle attached to each end of each of two of these ropes, a 10 bent link attached to each end of each of the other two of these ropes, an arm carried by each shackle bolt and adapted to engage a bent link, a socket mounted on an axle adapted to rotate and carried by the shackle, the 15 said socket being adapted to receive the said arm and to liberate it when the said axle is turned through an angle, a chain wheel keyed on the said axle, and a chain adapted to operate the said chain wheel.
4. Towing apparatus for marine vessels comprising four ropes, a shackle attached to each end of each of two of these ropes, a 20 bent link attached to each end of each of the other two of these ropes, an arm carried by each shackle bolt and adapted to engage a bent link, a socket mounted on an axle adapted to rotate and carried by the shackle, the 25 said socket being adapted to receive the said arm and to liberate it when the said axle is turned through an angle, a chain wheel keyed on the said axle, a chain adapted to operate the said chain wheel, an eye having a pulley groove in which the said chain slides, and a cord stretched between fixed 30 points parallel to the said towing ropes and in a plane above that containing said ropes, on which cord the said eye is adapted to slide.
5. A towing apparatus for marine vessels 40 comprising four ropes connected together by readily attachable and detachable shackles to form an endless cable, a pulley fixed to each vessel, two of the said four parts passing around the sheaves of the said pulleys.
6. A towing apparatus for marine vessels 45 comprising four ropes connected together by shackles, a pulley fixed to each vessel, two of the said four parts passing around the sheaves of the said pulleys, cheeks to the 50 said pulleys, each cheek having an eye and stops on the ropes that pass around the pulley sheaves adapted to engage in the said eyes.
7. Towing apparatus for marine vessels 55 comprising four ropes, a shackle attached to each end of each of two of these ropes, a bent link attached to each end of each of the other two of these ropes, an arm carried by each shackle bolt and adapted to engage a 60 bent link, a socket mounted on an axle adapted to rotate and carried by the shackle, the said socket being adapted to receive the said arm to liberate it when the said axle is turned through an angle, and means for 65 turning said axle.
8. A towing apparatus for marine vessels comprising a cable in four parts readily attachable and detachable connectors connecting said four parts into an endless cable, the cable being arranged with two portions of its length extending between the towing boat and the towed boat symmetrically and tending to equilibrate the strains, and two lateral pulleys on each vessel around which a part of the cable passes. 70
9. A towing apparatus for marine vessels comprising a cable in four parts readily attachable and detachable connectors connecting said four parts into an endless cable, the cable being arranged with two portions of its length extending between the towing boat and the towed boat symmetrically and tending to equilibrate the strains, and two lateral pulleys on each vessel around which a part of the cable passes, and means operable from each vessel for detaching the connections at the ends of the part of the cable which passes around the pulleys thereon. 75
10. A towing apparatus for marine vessels comprising a cable in four parts readily attachable and detachable connectors connecting said four parts into an endless cable, the cable being arranged with two portions of its length extending between the towing boat and the towed boat symmetrically and tending to equilibrate the strains, the middle 80 part of each of said portions consisting of a chain. 85
11. A towing apparatus for marine vessels comprising a cable in four parts readily attachable and detachable connectors connecting said four parts into an endless cable, the cable being arranged with two portions of its length extending between the towing boat and the towed boat symmetrically and tending to equilibrate the strains, each of 90 said portions having a middle consisting of a chain and pendant ends consisting of ropes. 95
12. A towing apparatus for marine vessels comprising a plurality of cables, each in four parts, readily attachable and detachable connections connecting the four parts of each into an endless cable, and each cable being arranged with two portions of its length extending between the towing boat and the towed boat symmetrically and tending to equilibrate the strains. 100
13. A towing apparatus for marine vessels comprising a plurality of cables, each in four parts, readily attachable and detachable connections connecting the four parts of each into an endless cable, and each cable being arranged with two portions of its length extending between the towing boat and the towed boat symmetrically and tending to equilibrate the strains, and two lateral pulleys on each vessel around which one of 105 said cables passes. 110
14. A towing apparatus for marine vessels comprising two portions extending be- 115

tween the towing boat and the towed boat and readily breakable and attachable at four points, one of which points in each portion is accessible from each boat.

5 15. A towing apparatus for marine vessels comprising an endless cable in four parts, a pulley on each vessel, two of the said parts passing around the sheaves of said pulleys and the other two of said parts 10 being lighter than the two parts passing

around the pulleys, and detachable connecting means connecting the four parts.

In witness whereof, I have hereunto signed my name in the presence of two subscribing witnesses.

LOUIS VICTOR WILLIAM FROGER.
